US0D1061285S

(12) **United States Design Patent** (10) **Patent No.:** **US D1,061,285 S**
(45) **Date of Patent:** **** Feb. 11, 2025**

(54) **LOCATION TRACKING DEVICE**

(71) Applicant: **Copenhagen Trackers ApS**, Tommerup (DK)

(72) Inventor: **Thomas Christian Olesen**, Odense (DK)

(73) Assignee: **Copenhagen Trackers ApS**, Tommerup (DK)

(**) Term: **15 Years**

(21) Appl. No.: **29/968,798**

(22) Filed: **Oct. 18, 2024**

Related U.S. Application Data

(62) Division of application No. 29/917,996, filed on Nov. 23, 2023.

(51) **LOC (15) Cl.** **10-04**

(52) **U.S. Cl.** **USPC .. D10/70**

(57) **CLAIM**

The ornamental design for a location tracking device as shown and described.

DESCRIPTION

FIG. 1 is a front, right and top perspective view of a location tracking device, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the location tracking device that form no part of the claimed design.

1 Claim, 8 Drawing Sheets
